CURTAIN ROLLER BRACKET

William S. Hamm, Elkhart, Ind., assignor to The
Adlake Company, Chicago, Ill., a corporation
of Illinois

Application December 27, 1932
Serial No. 648,839

11 Claims. (Cl. 156—24)

This invention has to do with the brackets which are used to support the spring wound curtain rollers at the windows of automobiles, and is particularly concerned with a novel bracket construction for use in that type of assembly wherein a retractable journaling trunnion is provided for the roller to facilitate application and removal of the latter.

One of the objects of the invention is to provide a bracket of improved construction which has a roller-supporting member retractably mounted therein.

Another object is to provide a roller-supporting member of improved construction which is easy to apply to the bracket.

Other more specific objects and advantages will be apparent to those skilled in the art upon a full understanding of the construction, arrangement and operation of the parts which together constitute the improved bracket.

Three different structural embodiments of the invention are presented herein by way of exemplification, but it will of course be appreciated that the invention is capable of embodiment in still other structurally modified forms coming equally within the scope of the appended claims.

In the accompanying drawing:

Fig. 1 is a top view of a bracket constructed in accordance with the invention, showing a curtain roller associated with the bracket;

Fig. 2 is a horizontal section through the bracket and roller;

Fig. 3 is an end view of the bracket;

Fig. 4 shows, in separated relation, the parts which are adapted to be combined to form the retractable trunnion;

Fig. 5 is a section through a modified form of the bracket;

Fig. 6 shows, in separated relation, the parts which are adapted to be combined to form the trunnion for the bracket illustrated in Fig. 5;

Fig. 7 is a section through another modified form of the bracket;

Fig. 8 shows the trunnion for the bracket which is illustrated in Fig. 7; and

Fig. 9 is a section through the head of the bracket shown in Fig. 7, taken on the line 9—9 of Fig. 7.

The bracket which is shown in Figs. 1 to 4 inclusive consists of an L-shaped sheet metal stamping 10 and a cup-shaped sheet metal stamping 11. One leg 12 of the stamping 10 is provided with holes 13 for the reception of the usual attaching screws, while the other leg 14 terminates in a circular end portion 15, which portion

is provided at its center with an aperture 16. The cup-shaped stamping 11 has its rim 17 inturned about the edge of the circular portion 15 of the stamping 10 and forms with the same a hollow head 18. The stamping 11 is provided at its center with an aperture 19 which is arranged in alignment with the aperture 16.

A trunnion 20 is slidably mounted in the head 18, in the apertures 16 and 19 in the outer and inner walls of the head, with the inner end 21 of the trunnion projecting a substantial distance beyond the inner wall into a journaling socket 22 in one end of the associated roller 23. The other end of the trunnion projects slightly beyond the outer wall of the head and terminates in a finger piece 24 which fits closely up against the outer wall. The trunnion 20 is surrounded, within the head of the bracket, by a coil spring 25, which spring is confined between the outer wall of the head and an annular rib 26 on the trunnion. The finger piece 24—which is used in retracting the trunnion against the action of the spring—serves to limit the axial movement of the trunnion toward the roller 23, while the rib 26 limits the movement of the trunnion in the opposite direction when it is retracted to disengage the projecting end 21 of the trunnion from the socket 22 in the roller.

As will be observed in Fig. 4, the trunnion 20 is made up of two parts, one a tube 27 and the other a headed pin 28. The tube 27 is upset intermediate its length to form the annular rib 26 on the trunnion. In assembling the bracket, the tube 27 and the spring 25 are placed in position before the cup-shaped stamping 11 is attached to the stamping 10. After the stamping 11 has been attached, the pin 28 is inserted in the tube 27 and the end 29 of the pin is then riveted out over the end 30 of the tube. The head of the pin forms the finger piece 24.

In the modification which is shown in Figs. 5 and 6 the hollow head formation of the bracket is substantially the same as in the first described embodiment of the invention but the retractable trunnion 31 is made in a somewhat different way. In this form of the invention, the trunnion consists of a solid pin which is provided intermediate its ends with an annular rib 32. The outer end 33 of the pin is reduced in diameter and is adapted to receive a small washer 34 after all of the other parts have been assembled. After the washer 34 has been applied, the reduced end 33 of the pin is headed over the washer at 35, thereby forming a finger piece on the outer end of the trunnion for use in retracting the latter from 110.

the socket in the roller against the action of the spring.

In the modification which is shown in Figs. 7 and 8, the spring is dispensed with and the trunnion 36 is made in one part instead of two. In this embodiment, the cup-shaped stamping 37 is shown as countersunk about the aperture 38 in order to provide a recess for the reception of the finger piece 39 on the outer end of the trunnion. The trunnion 36 is prevented from being entirely withdrawn from the head of the bracket by means of a pair of diametrically opposed tongues 40 on the stamping 37, which tongues press more or less resiliently with a certain amount of friction against the shank of the trunnion and are adapted to engage within abrupt wall notches 41 in the shank after the trunnion has been retracted far enough to clear the end of the roller. The frictional engagement of the tongues 40 with the shank of the trunnion is preferably such as to prevent any likelihood of the trunnion working out of the roller except when forcibly withdrawn from the same by means of the finger piece 39. In this form of the invention the trunnion 36 can be inserted in the head of the bracket after the latter has been fully assembled, and when once inserted it cannot be withdrawn beyond a certain point, which point is determined of course by the location of the notches 41 with respect to the tongues 40.

I claim:

1. In a curtain roller bracket, a head, and an axially retractable roller-supporting member which is secured in the head and is designed for coaction with an aperture in one end of a curtain roller.
2. In a curtain roller bracket, a head, and an axially retractable roller-supporting member mounted in the head, and means on the head to limit the movement of the member in both directions with respect thereto.
3. In a curtain roller bracket, a hollow sheet metal head provided with aligned apertures in its outer and inner walls, a roller-supporting member slidably mounted in said apertures, a finger piece on the outer end of the member adjacent the outer wall of the head for use in retracting the member, and a spring in the head for yieldingly resisting retraction of the member.
4. In a curtain roller bracket, a hollow sheet metal head provided with aligned apertures in its outer and inner walls, a roller-supporting member slidably mounted in said apertures, a finger piece on the outer end of the member adjacent the outer wall of the head for use in retracting the member, a spring in the head for yieldingly resisting retraction of the member, and means for limiting the extent of retraction.
5. In a curtain roller bracket, a hollow sheet metal head provided with aligned apertures in its outer and inner walls, a roller-supporting member slidably mounted in said apertures, a finger piece on the outer end of the member adjacent the outer wall of the head for use in retracting the member, a spring in the head for yieldingly resisting retraction of the member, and

means for limiting the extent of retraction, said roller-supporting member consisting of a tube which is provided intermediate its ends with an annular shoulder, and a headed pin which passes through said tube and is riveted against the inner end of the latter.

6. In a curtain roller bracket, a hollow head having aligned apertures therein, a roller-supporting member which is slidably mounted in the apertures in the head, and a spring in the head for yieldingly resisting retraction of the member, said member being provided interiorly of the head with an annular shoulder for engagement with the spring and being provided exteriorly of the head with a finger piece for use in retracting the member against the yielding resistance of the spring.

7. In a curtain roller bracket, an L-shaped sheet metal stamping having a generally circular end portion which is provided at its center with an aperture, a cup-shaped sheet metal stamping which has its rim inturned about the edge of the circular portion of the first stamping and is provided at its center with an aperture in alignment with the first mentioned aperture, a roller-supporting member slidably mounted in said apertures, a finger piece on the outer end of the member beyond the cup-shaped stamping for use in withdrawing the other end of the member from engagement with a roller, and means for limiting the extent of movement of the member.

8. In a curtain roller bracket, an L-shaped sheet metal stamping having a generally circular end portion which is provided at its center with an aperture, a cup-shaped sheet metal stamping which has its rim inturned about the edge of the circular portion of the first stamping and is provided at its center with an aperture in alignment with the first mentioned aperture, a roller-supporting member slidably mounted in said apertures, a finger piece on the outer end of the member beyond the cup-shaped stamping for use in withdrawing the other end of the member from engagement with a roller, and means within the cup-shaped stamping for limiting the extent of movement of the member.

9. In a curtain roller bracket, a head, and an axially retractable roller-supporting member mounted in the head, said member consisting of a tube which is provided intermediate its ends with an annular rib, and a headed pin which is fixedly secured within said tube.

10. In a curtain roller bracket, a head, and an axially retractable roller-supporting member mounted in the head, said member consisting of a pin which is provided intermediate its ends with an annular rib and is provided at its outer end with a reduced portion, and a washer which is fixedly secured on said reduced portion.

11. In a curtain roller bracket, a hollow head, and an axially retractable roller-supporting member mounted in the head, said member consisting of a pin which is provided interiorly of the head with means for limiting the extent of retraction of the member.
